UNITED STATES PATENT OFFICE.

JOHN S. ELLIS, OF ST. LOUIS, MISSOURI.

DESIGN FOR A SCRAPER.

54,310.

Specification for Design.

Patented Dec. 23, 1919.

Application filed September 3, 1918. Serial No. 252,494. Term of patent 14 years.

To all whom it may concern:

Be it known that I, JOHN S. ELLIS, a citizen of the United States, residing at the city of St. Louis, State of Missouri, have invented a new, original, and ornamental Design for Scrapers, of which the following is a specification, reference being had to the accompanying drawing, forming a part thereof.

The drawing illustrates a scraper embodying my new design, Figure 1 being a side elevational view, Fig. 2 being a front elevational view, Fig. 3 being a plan view, and Fig. 4 being an inverted plan view.

My design for scrapers comprises a flat base or body portion A circular in shape in plan view. Rising from and extending vertically or perpendicularly around base A is a decorative upright marginal flange B, a portion of flange B being extended upwardly and vertically into a finger-grip C. The finger-grip C is of concavo-convex shape

in cross-section, the concave side appearing on the inside in continuation of the inner curve or surface of the flange B, and the convex side appearing on the outside in continuation of the outer curve or surface of the flange B, and adjacent its upper end the finger-grip C is laterally bent outwardly and terminates in a gentle curve, as at c, which merges into a substantially flat portion having a rounded edge. Base A, substantially throughout its area, has a multitude of relatively small circular apertures or perforations a appearing on the inner surface in a series of concentric circular rows, and on its under face, has a multitude of rough protuberances a', appearing as a series of concentric circular rows of nested points or teeth.

I claim:

The ornamental design for a scraper substantially as shown and described.

JOHN S. ELLIS.
